Primary Examiner — Paula Allen Greene(74) *Attorney, Agent, or Firm* — Scott H. Kaliko, Esq.;
Kaliko & Associates, LLC(57) **CLAIM**

An ornamental design for wireless ear bud, as shown and described.

DESCRIPTION

FIG. 1 is a PERSPECTIVE view of a wireless ear bud of the present invention;

FIG. 2 is a TOP view of an embodiment of the present invention;

FIG. 3 is a BOTTOM view of an embodiment of the present invention;

FIG. 4 is a SIDE view of an embodiment of the present invention;

FIG. 5 is a SIDE view of an embodiment of the present invention;

FIG. 6 is a FRONT view of an embodiment of the present invention; and,

FIG. 7 is a BACK view of an embodiment of the present invention.

The broken lines depict environment that forms no part of the claimed design.

1 Claim, 4 Drawing Sheets(56)
